Solyman Merrick Springfield Mass
Letters Patent.

The Schedule referred to in these Letters Patent and making part of this document containing a description in the words of the said Solyman Merrick himself of his improvement in the Rock Bunch.

To all to whom it may concern. I Do it know that I Solyman Merrick of Springfield in the County of Hampden and State of Massachusetts have invented an improvement in the Rock Bunch invented by Henry King and for which Letters Patent of the United States were granted to him on the 25th of October 1832. And I do hereby declare that the following is a full and exact description of my said improvement.

The main bar, the slide and the spring click may be made in the same form and manner of those in the original Rock bunch upon which this is an improvement, but instead of cutting the notches in which the spring click is to catch, directly upon the main bar. I make a sliding Rock of such length as may be necessary to regulate the distance of the jaws from each other, which Rock I place in a groove in the upper side of the bar. Upon this sliding piece I cut either notches to receive the spring click either at equal or at graduated distances from each other. This sliding piece or movable Rock is to be acted upon by a screw which must cause it to move backward & forward to a distance equal to that of the widest tooth in the Rock. What I deem one of the best methods of arranging the parts so as to accomplish this end is the following. I make the shank of the bar on that part of it which bears the handle round & form a square shoulder at the point where the square bar commences. on this round part I drive a turned collar which bears against the square part of the bar and transforms a flange which holds one end of a nut or fastener in its place which passes on to and makes freely against it. A groove is made through this collar communicating with that on the main bar, that the rearend of

end of the sliding rack before described may pass thro' it. On this end of the Rack spiral grooves are cut which match into the threads of a female screw cut upon the inside of the revolving nut or female just alluded to. This revolving female is then passed on to and against the aforesaid ~~inner~~ collar, being screwed round so that the threads on its inner surface may take on the spiral grooves which form a segment of a male screw on the end of the rack.

Another circular collar of the same diameter with the former which is equal or nearly equal to that of the revolving nut or female is then driven over the shank and against the nut but not so closely as to interfere with the revolving motion. The wooden handle may then be driven on the shank and riveted in its place. The outer surface of the nut should be milled that it may be more readily turned round by the hand. It will be seen that by this arrangement whenever the slide is placed to the most desirable point on the rack, the jaws can be readily and precisely adjusted by turning the nut. Although I have pointed out what I desire to be the best mode of arranging the parts, & as to adjust the sliding Rack, I do not intend therefore to confine myself to this particular arrangement but to vary the same in any way which is in accordance with the general principles of mechanical action having before & for the end by which a similar effect is produced limiting myself in my claim to improvement to the addition of the revolving sliding rack operated upon and adjusted by a screw.
